UNITED STATES PATENT OFFICE

CHRISTOPHER H. BIERBAUM, OF BUFFALO, NEW YORK

FIREARM

Application filed November 16, 1928. Serial No. 319,752.

This invention relates to fire arms, and more particularly to the barrel of the same so as to improve the accuracy of flight of the projectile as it leaves the muzzle of the barrel.

Heretofore the bore of gun barrels have been rifled so as to produce therein grooves and lands which alternated circumferentially and extended unbroken to the outer end of the muzzle. When firing a projectile or bullet the base of which is not at right angles to the axis of the same or to the axis of the bore of the barrel this inaccuracy of the base of the bullet will materially influence the accuracy of its flight. This inaccuracy is due to unbalanced side pressure upon the rear end portion of the bullet owing to the fact that the gas pressure of the muzzle blast starts on the shorter side of the bullet before this pressure acts on the longer side of the same, because the short side of the bullet leaves the muzzle before the long side of the same has cleared the barrel. It follows from this uneven pressure against the sides of the bullet at the rear end of the same a lateral deflection in the course of its projection occurs and this effects inaccuracy in its flight.

Not only is such inaccuracy in the flight of a bullet due to defective ammunition when manufactured, but such inaccuracy in the bullet is also produced as the same passes through the length of the barrel because the base of the bullet under the pressure of the gas resulting from the ignited powder and passing through a rough or worn barrel cannot be kept as true as though the bullet were pushed through a swedging die by a plunger.

My invention therefore contemplates the provision of simple and efficient means for improving the barrel of fire arms so as to secure accuracy in the flight of the bullet issuing from the muzzle of the bore thereof, and to that end the improvement consists in so organizing these means that the blast of the exhaust as it issues from the muzzle of the barrel will be equalized around the entire circumference of the projectile at the time it is discharged from the muzzle of the barrel.

In the accompanying drawings:

Fig. 1 is a front view of the muzzle of the

barrel of a firearm constructed in accordance with one form of my invention.

Figs. 2 and 3 are fragmentary longitudinal sections of the same, taken on the correspondingly numbered lines in Fig. 1.

Fig. 4 is a diagrammatic representation showing the bore of the barrel shown in Figs. 1, 2 and 3 developed on a plane.

Fig. 5 is a front end view of the firearm barrel showing a modified form of my invention.

Figs. 6 and 7 are fragmentary longitudinal sections of the same, taken on lines 6—6 and 7—7, Fig. 5, respectively.

Fig. 8 is a diagrammatic view of the structure shown in Figs. 5, 6, and 7 developed on a plane.

In the following description similar characters of reference indicate like parts in the several figures of the drawings.

Referring to the construction shown in Figs. 1—4, the numeral 10 represents the barrel of a firearm which may be either a rifle, cannon or the like adapted to propel a bullet or projectile 11 with a forward movement 75 lengthwise of its axis and a rotary movement around the axis thereof.

The bore of the barrels of such firearms is usually provided with helical grooves 12 and lands 13 alternating circumferentially around the surface of this bore whereby the bullet in its forward passage through this bore under the pressure of the gases resulting from the ignited charge of powder will also be rotated about the axis of the bullet and this bore due to the effect of the driving edges 14 of the lands 13 which latter embed themselves in the periphery of the bullets or projectiles while being forced lengthwise through the barrel.

In the absence of any provision to prevent it any bullet or projectile having its rear end or face 15 arranged at an oblique angle to the axis of the bullet or the barrel, as shown in exaggerated form in Figs. 2, 3, 6 and 7 will be deflected laterally upon being discharged from the muzzle of the barrel due to the pressure of the exhaust blast acting against the short side of the bullet in advance of the

long side thereof, thereby causing inaccuracy in the flight of the bullet.

To ensure accuracy in the flight of the bullet, the muzzle of the barrel is provided with means which operate to equalize the pressure of the exhaust blast at the muzzle around the entire circumference of the bullet at the time of its discharge from the barrel.

This is preferably accomplished by providing the bore of the barrel at the muzzle with an annular series of equidistant notches or relief passages 16 which extend from the bore radially outwardly and forwardly to the front end of the barrel, and have their inner ends beginning on the same plane arranged at right angles to the axis of the barrel.

These notches begin at their inner ends at the bottom of the grooves in the bore, as shown in Figs. 1, 3, 4, 5, 7 and 8, and each notch may be formed either wholly within the range of one of the grooves, as shown in Figs. 5-8, or each notch may extend circumferentially far enough to cut off the extreme front part 17 of the driving edge 15 of the adjacent land, as shown in Figs. 1, 3 and 4.

When a bullet is discharged from the muzzle having its rear face arranged at right angles to its axis, as shown by dotted lines 18, in Figs. 2, 3, 6 and 7, the pressure of the exhaust blast will be released equally and at the same time so as to produce a uniform side pressure around the entire circumference of the bullet, the instant that the rear end of the bullet begins to uncover the rear or inner ends of the equalizing notches in the bore of the barrel and this uniform side pressure of the exhaust continues, while the rear portion of the bullet is still guided axially relatively to the bore of the barrel due to the lands remaining in engagement circumferentially with the periphery of the bullet.

If a bullet having its rear face more or less oblique relative to the axis of the same or the barrel, as shown by full lines at 15 in Figs. 2, 3, 6 and 7, is discharged from the muzzle of the barrel the rear end of that side of the bullet which is comparatively short will uncover the inner end of the respective equalizing notch slightly in advance of the time when the rear end of the comparatively long side of the bullet also uncovers the inner end of the respective equalizing notch. Although the exhaust blast under these conditions would be released and exert a side pressure against the short side of the bullet before any side of the exhaust blast is exerted against the long side of the same, such unbalanced side pressure against the bullet will not be able to deflect the bullet out of its straight axial course ahead because the bullet will be held in line by the front end of the lands until after the long side of the bullet has also uncovered the respective equalizing notches and thereby permits the exhaust

blast to exert a pressure against the entire circumference of the bullet before leaving the lands, whereby accuracy in the flight of the bullet is ensured.

When the equalizing notches are formed solely in line with the companion grooves in the bore of the barrel, as shown in Figs. 5-8, the driving edges of the lands continue their grip and exert a rotative effect on the bullet until the latter has been completely discharged from the barrel.

If, however, the equalizing notches are extended circumferentially so as to take off the front ends of the driving edges of the lands, as shown at 17, the rotative constraint of these driving edges on the bullet ceases, the instant the rear end of the latter clears these driving edges but is still momentarily guided axially thereby while the exhaust blast completes the propulsion of the bullet from the barrel and also envelopes the bullet circumferentially on all sides before the same is discharged from the barrel, thereby further increasing the accuracy in the flight of the bullet. The final discharge of the projectile is therefore made under its own inertia, both propulsion and rotation, with an even muzzle blast around its base as it leaves the bearing provided only by the lands of the barrel.

It will be apparent from the foregoing that this improvement can be embodied in firearms at small cost and without altering any parts thereof, and that the addition of this improvement renders it possible to fire imperfect bullets of the character described with the same accuracy that is obtained by the use of perfect bullets, thereby obtaining more satisfactory results from the use of firearms.

Although I have herein shown and described the preferred forms of my invention, it is to be understood that the same may be varied within the scope of the appended claims without sacrificing any of its essential features.

I claim as my invention:

1. A firearm barrel provided at the muzzle of its bore with notches opening throughout their length into said bore whereby gas pressure is caused to immediately engage the side of the projectile before the latter leaves the muzzle.

2. A firearm barrel provided in its bore with alternating helical grooves and lands, and notches opening throughout their length into the grooves at the muzzle of the barrel whereby gas pressure is caused to immediately engage the side of the projectile before it leaves the muzzle.

3. A firearm barrel provided in its bore with alternating helical grooves and lands, and notches which open into the grooves and cut off the driving edges of the lands at the muzzle of the barrel.

4. A firearm having its barrel provided with means for equalizing the exhaust blast on the base of a projectile by engaging the blast immediately with the side of the rear 5 part of the projectile while the same leaves the muzzle of the barrel.

5. A firearm having the bore of its barrel provided with means for rotating the projectile while projecting the same, and also 10 having means for equalizing the pressure of the exhaust blast upon the base of the projectile without rotative constraint of the same upon leaving the barrel and immediately engaging the blast with the side of the projectile adjacent to its base before the same leaves 15 the barrel.

In testimony whereof I hereby affix my signature.

CHRISTOPHER H. BIERBAUM.
